[57] CLAIM

The ornamental design for a washstand, substantially as shown and described.

DESCRIPTION

FIG. 1 is a perspective view taken from the top, front and right side of the washstand showing my new design; FIG. 2 is a top plan view thereof;

FIG. 3 is a front elevational view thereof;

FIG. 4 is a right side elevational view thereof; the left side being a mirror image of the side shown;

FIG. 5 is a rear elevational view thereof; and

FIG. 6 is a bottom plan view thereof.
